POLISHING BRUSH

Filed Oct. 24, 1928

Fig. 1. Fig. 2. Fig. 3.

UNITED STATES PATENT OFFICE

CLINTON E. FROST, OF YOUNGSTOWN, OHIO, ASSIGNOR, BY MESNE ASSIGNMENTS, TO THE PITTSBURGH PLATE GLASS COMPANY, OF PITTSBURGH, PENNSYLVANIA, A CORPORATION OF PENNSYLVANIA

POLISHING BRUSH

Application filed October 24, 1928. Serial No. 314,708.

The objects of the invention are to provide an improved construction for a disc shaped polishing-wheel or brush, said brush having radially directed wires or bristles, which are gathered into tufts that are looped over a central retaining ring. The tufts are mounted between rigid sheet metal discs which provide a hub therefor and complete a unitary structure.

10 In practice a multiple number of these discs, according to the width of the brush required, are sleeved over a common arbor or mandrel and securely clamped thereon.

The device is an improvement upon my former Patent No. 1,683,456 granted upon Sept. 4, 1928, for a disc shaped brush in which the discs were provided with openings of the same diameter as the arbor or mandrel, thus suiting them to all mandrels of the same diameter. If a mandrel of smaller diameter was to be used, a reducer of the opening in at least one of the discs, was required.

In the present invention, however, one disc may be provided with a large opening which may be of stock standard size, for the reception of a large number of mandrels of different sizes. The other disc is provided with an opening that is reduced in size to agree with the diameter of the particular mandrel to be employed therewith, thus greatly simplifying the production of the discs, since the discs having the openings of greater diameter, can be produced as a standard production, and the other discs can be formed as blanks and openings can be made therein to suit the customer's order, and may be made of a much smaller diameter than that of the other disc.

15 The several tufts of wires or bristles comprising the body of the brush are composed of loops which are secured together by means of a central ring passing through the loops, in one method of construction, thus forming a unitary brush body. Each disc is attached to the body by means of integral lugs or keepers stamped therefrom. The lugs are turned at right angles and driven through the body of the brush, after which they are clinched over the bristles or wires upon the other side.

20 The discs are so disposed that the points of

the lugs upon one disc enter the openings in the other disc and are flattened down therein over the brush body, thus preserving a smooth, even, external surface on both sides of the brush. This arrangement also permits of the attachment of the second disc after the first one has been secured to the brush body.

25 The lugs act in the manner of staples to bind all of the parts together and are inserted between the holding rim and the outer ends of the bristles. The loop method of constructing the tufts prevents the bristles from escaping singly from the brush body, and the lugs form interlocking staples to hold 30 the discs tightly to the body.

35 The invention is illustrated in the accompanying drawing hereinafter more fully described and particularly pointed out in the claims.

40 In the accompanying drawing Fig. 1 is a side elevation of the brush showing openings of dissimilar diameter in the discs; Fig. 2 is a transverse central section therethrough; Fig. 3 is a transverse section on line 1-1 45 Fig. 1, showing the overlapping lugs; Fig. 4 is a perspective of a disc having the large or standard or stock size of opening therein, and Fig. 5 is a similar perspective showing the disc having the smaller opening, which is 50 fitted to the diameter of a particular mandrel; Fig. 6 is an edge elevation of a brush composed of flat wires. Fig. 7 is a vertical section thereof. Fig. 8 is a perspective of one looped flat wire, and Fig. 9 is a section 55 taken at right angles to Fig. 7 showing the manner of securing the wire loops over the fastening lugs of the side plates.

60 In these views A is the body of the brush which is composed of looped tufts of wire or bristles secured radially upon a central wire ring B; C and D, are sheet metal discs between which the body of the brush is clamped and which when in position form the hub 65 of the brush.

65 The discs are provided with central openings C' and D'. The disc C having a relatively large opening is adapted for use with a large number of mandrels, but the disc D is formed with a central opening of such 70

diameter as to fit exactly a particular mandrel. The center of this disc is also depressed or is offset and shouldered axially in cross section at D² to reinforce the same and to form a bearing or support for the tufts of brushes, thereby preventing them from being pushed inwardly when force is applied to their outer ends. Each disc is separately attached to the body in a rigid manner by forming pointed lugs F F, therein intermediate of its inner and outer edges, these lugs being struck from the bodies of the discs, leaving triangular openings G G therein.

15 The lugs in one disc are forced through the brush body between the strands thereof and the points are turned over and clinched upon the other side of the brush body. The other disc is similarly attached by means of the 20 lugs therein which are driven through the body in the opposite direction. The last disc is so positioned that when the pointed lugs are forced through the brush body the points will enter the openings made in the first 25 placed disc and will be clinched therein, so that the entering lugs will pass each other as shown in Fig. 2, and the points thereof will be turned in opposite directions.

30 In this manner the flat side of the discs will be smooth and capable of being applied closely together, as shown in Fig. 6. The discs and wires are carried in stock before assembling the parts; as shown, one disc C carries half of the tufts of wires and the 35 other disc D carries the other half of the tufts.

30 In Fig. 2 the position of the arbor or mandrel is shown in dotted lines at H and is engaged only by the inner edge of the smaller opening D' which serves as a bearing therefor. Since a multiple number of discs are 40 pressed closely together to form an elongate sectional brush, this manner of support will be secure and rigid and the brush can not be inclined out of the vertical plane.

45 In Figs. 6, 7, 8 and 9 the brush is shown adapted for use with flat wire, the long edges of the wires being paralleled with the longitudinal axis of the brush.

50 Here A' are the wires, which are formed into tufts looped over the transverse stapling points F, and secured from being pushed inwardly by means of the shoulder D² upon the disc D. When the discs are attached to the brush body the tufts will be immovable 55 therein.

Having described the invention what I claim as new and desire to secure by Letters Patent is.

60 1. In a polishing brush, a body composed of looped wires and a sheet metal disc secured to each side thereof, one of said discs providing a hub therefor, one disc being provided with a central opening and the other disc being provided with a central opening

of lesser diameter for the reception of a mandrel of a particular diameter, the marginal wall of said opening in the disc having the lesser opening being offset axially to position the edge of said lesser opening substantially in the central plane of said brush and axially spaced from the other disc.

2. In a polishing brush, a brush body and a sheet metal disc secured upon each side thereof, each disc being provided with a central opening, the opening in one of said discs forming a bearing for a mandrel, said bearing being offset axially and positioned substantially in the central plane of said brush and axially spaced from the other disc.

80 In testimony whereof I affix my signature.

CLINTON E. FROST.
